SPARK INTENSIFIER

Emmett M. Robinson, San Francisco, Calif.

Application October 2, 1943, Serial No. 504,757

5 Claims. (Cl. 123—148)

This invention relates to a spark intensifier for use in connection with distributors on internal combustion engines.

One of the objects of the invention is a single, durable, economical device adapted to be positioned in the high tension conductor leading to the distributor or to be interposed between said conductor and the distributor, and which device functions during the operation of such engine to substantially eliminate objectionable deterioration and carbonization of the spaced points forming the spark gap of the spark plugs, which latter are connected by conductors with the distributor.

Another object of the invention is a spark intensifier constructed to greatly increase the efficiency of the spark produced at the spark gap in a spark plug in a manner to insure an effective spark for effecting a more complete combustion of gases in an internal combustion engine than heretofore without objectionable carbonization or burning of the spark points, and also, where my intensifier is used it functions to insure an effective spark at said spark gap even in the event of a leakage in the insulation of the spark plug to such an extent that no effective spark is produced at the gap in present systems.

The ultimate results accomplished by my intensifier are: substantial elimination of present spark plug troubles over long periods of time for exceeding the ordinary life of spark plugs in conventional installations, not using my intensifier; an increase in power of the engine by reason of more effective ignition of the combustible gases; smoother operation of the engine due to positive ignition at each firing point in the firing cycle; increased economy in the operation of an engine. Other results are accomplished as already noted herein.

In the drawing,

Fig. 1 is an enlarged vertical sectional view through my device, in position on a conventional distributor, and with certain elements in the device as well as one end of the high tension electrical conductor being shown in elevation.

Fig. 2 is a sectional view taken along line 2—2 of Fig. 1.

In detail, the portion of a conventional distributor adapted to support my device is indicated at 1, and which portion comprises a centrally recessed cylindrical boss, having therein a conductor element 2 adapted to be frictionally gripped by a tubular conductor sleeve extending from my device.

My device itself comprises a body member 3 of

insulation material, such as "Bakelite," hard rubber, or any other suitable electrical insulating material. This body member is elongated and is formed with a cylindrical through bore extending longitudinally thereof and opening outwardly of the body at its opposite ends.

For convenience of description, my device will be considered as being positioned vertically as shown in the drawing, although in actual use it may be supported in any other position should the distributor or the support therefor be adapted to support the device in any position other than vertical.

The lower end portion 4 of the bore through my device is of less diameter than the remaining upper portion 5 thereof, thus forming an annular shoulder 6 at the juncture between portions 4, 5.

A metal conductor tube 7 of outside diameter substantially that of the portion 4 of said bore is inserted into the upper open end of portion 5 and is moved into said bore until the slightly outwardly flared rim 8 formed around the upper end of said tube rests against the shoulder 6. The length of said tube 7 is such that its lower end projects a substantial distance from the lower end of the body 1. This lower end of tube 7 is preferably vertically slotted from the lower edge of the tube so that the lower end portion of the tube may be frictionally secured to the end of conductor 2.

Within the bore 5 is a cylindrical, open-ended tube 9 of insulation material such as glass, which tube freely slides in bore 5. At the end of tube 9 adjacent the rim 8 is a cylindrical metal sleeve 10 provided with an outwardly projecting flange 11 at one end, which flange is adapted to seat on rim 8. The sleeve 10 is adapted to extend into tube 9 a short distance, and at the opposite end of tube 9 is a sleeve 12 that is similar to sleeve 10. This sleeve 12 has a flange 13 corresponding to flange 11, but disposed at the upper end of sleeve 12, and which flange 13 seats against an annular metal disk 14 that is secured in bore 5 at a point spaced from the upper open end of said bore.

The flanges 11, 13 are preferably slightly spaced from the ends of tube 9 as seen in Fig. 1, and the sleeves 10, 12 are spaced within the opposite ends of said tube.

Intermediate the opposite ends of tube 9, and therein, is a plurality of circular disks 15 of highly refined tungsten, being almost pure or over 99% pure. Each of these disks are separated from each other by a circular disk 16 of relatively thin mica and the tungsten and mica disks are

of substantially the same diameter and are slideable in tube 9, being slightly smaller in diameter than the inside diameter of said tube.

A coil spring 17 of phosphor bronze having adjacent turns of the coil relatively well open is interposed between flange 13 and the upper disk 15 while a similar spring 18 of the same material is interposed between the lower disk 15 of the pile and the flange 11. These springs and said disks are, of course, assembled in tube 9 and between the flanges 13, 11 before the annular disk 14 is secured in bore 5, and said springs are of sufficient length to yieldably hold the disks 15, 16 together, and to hold the flanges 11, 13, respectively against rim 8 and disk 14 when the latter is secured in bore 5.

The body 3 is generally cylindrical with the coaxial bores 4, 5 centrally therein, and as all elements in said bores, such as the sleeves 7, 10, 12, rim 8, flanges 11, 13, disks 14, 15, 16, springs 17, 18 and tube 9 are all coaxial with the central axis of the body 3, it is seen that the device is very easily assembled, the elements thereof are such as lend themselves to quantity production and assembly without requiring complicated and expensive dies, jigs, etc.

In most automobiles the insulated high tension conductor 19 is usually formed with a cylindrical terminal 20 at its end that is adapted to be frictionally held in the recess in the distributor boss and in contact or engagement with the conductor 2 in the latter. The upper end of bore 5 is adapted to frictionally hold the conductor terminal 20 in engagement with disk 14. Hence, to install my device on the conventional distributor, it is only necessary to remove terminal 20 from the latter, and to substitute the projecting end of sleeve 7. The terminal 20 is then positioned in the upper end of bore 5 and the device is in position for use.

In operation the high voltage current passing through spring 17 to the pile of disks 15 jumps from many points on the peripheries of the disks 15 across the slight gaps formed by mica disks 16 in its passage to spring 18 on the way to the spark gap of each spark plug when the distributor brush or rotor closes the circuit between the high tension conductor 19 and the conductor leading to each plug.

While the disks 15 and their separators of mica could have any desired shape other than circular, it is important that they be arranged so as to permit the passage of current from one disk to another at any point around the peripheries of said disks 15. Also, it is essential that the disks 15 be of a material, such as tungsten, since the softer metals lack sufficient resistance to deterioration under the substantially constant usage required in operation of an automobile or an internal combustion engine.

The use of more than a single pair of disks 15 providing a single spark gap in the intensifier is also important, since a single gap will not produce the desired results. There should be a plurality of gaps of substantially the character disclosed in order to obtain the best results, and I have discovered that the maximum results are obtained with substantially the number disclosed in the drawing.

While it is to be understood that this invention is not to be restricted as to dimensions of elements, I have found that using disks about $\frac{3}{64}$ to $\frac{1}{16}$ of an inch in thickness, and a diameter of about $\frac{1}{4}$ of an inch, with a gap of about $\frac{1}{64}$ to $\frac{1}{32}$ of an inch between disks, is highly satisfactory.

Of course, one or two disks or more of mica may be used between adjacent disks of tungsten to give the spacing desired. Mica is specified herein because it produces the desired effective insulation irrespective of temperature variations, but it is to be understood that any insulator or metal may be used provided it possesses the equivalent properties of those specified, and the same is true of the phosphor bronze springs. These springs have durability under most severe usage as have the disks of tungsten and mica. For all practical purposes, the spark intensifier as a whole may be said to be substantially indestructible barring occurrence of unusual accidents thereto.

From numerous tests conducted under actual operating conditions, there appears to be substantially no carbonization on the spark plug points or along the elements forming said points. Oil on such elements in an ordinary circuit rapidly commences smoking, leaving a carbon deposit, but with my intensifier there is no smoking and no deposit, but instead there is a sharp clean spark localized at the desired point. The conventionally produced spark appears yellowish with a luminous haze or field around the gap, whereas the spark produced with my intensifier in place is a fast, clean, blue spark, free from any halo or haze or yellowish cast. Where an insulator on a spark plug is leaky, either by reason of porosity or breakage, there is but little loss of efficiency at the spark gap when my intensifier is in the circuit, but in the usual circuit the plug is practically valueless insofar as producing an effective spark for combustion is concerned.

While I am aware that others have produced devices intended to intensify the spark at the spark gap in spark plugs by producing a spark gap in the high tension line leading to the distributor, I am not aware of any intensifier that produces an efficient and reliable intensifier adapted to accomplish the results of the one herein disclosed.

Having described my invention, I claim:

1. A spark intensifier comprising a row of metal disks and a row of electrical insulator disks in axial alignment with the said insulator disks between adjacent pairs of said metal disks insulating said metal disks from each other; a body member of electrical insulation material enclosing said metal disks and said insulator disks; yieldable electrical conductor means in said body respectively engaging the end metal disks of said row for yieldably holding said metal disks and said insulator disks in assembled relation; and means for engaging said electrical conductor means with the wires of a high tension circuit connected with a spark plug with said disks in series with such circuit to provide a plurality of spark gaps in said circuit before the current reaches such plug.

2. A spark intensifier comprising a tubular member having a cylindrical through bore; a row of circular disks of uniform diameter in said bore and substantially coaxial therewith; the alternate disks in said row being of metal and of electrical insulation material arranged so that the end disks are metal; yieldable electrical conductor elements in said bore engaging said end disks respectively and floatingly supporting said row of disks in said bore for axial movement to a position in said bore in which the yieldable resistance of said conductors against said end disks is equalized; means supporting said conductor elements against said end disks under

tension for yieldably holding the disks of said row together; and means for supporting the ends of high tension conductors in a high tension circuit in engagement with said yieldable conductors whereby a plurality of spark gaps in such circuit is provided between the peripheries of the metal disks of said row.

3. In a construction as defined in claim 2, a tube of rigid insulation material in said bore and substantially coaxial therewith enclosing said disks; the inner surface of said tube being glazed and said tube being axially movable in said bore between predetermined limits; stop means in said bore spaced from the opposite ends of said tube for limiting such movement of the latter.

4. A spark intensifier comprising a tubular member of refractory electrical insulation material having a cylindrical relatively highly glazed through bore, a row of circular metal disks in said bore coaxial therewith and a circular disk of electrical insulation material between the disks of each adjacent pair in said row, means at opposite ends of said member for connecting

the end metal disks of said row with electrical conductors in a high tension circuit, the inner diameter of said member being slightly greater than the diameter of the disks in said row to provide a slight space between the edges of said disks and the glazed surface of said bore.

5. A spark intensifier comprising a vitreous tubular member of electrical insulation material having a through bore formed with a relatively highly glazed surface, a row of tungsten disks within said bore coaxial therewith, and a disk of mica between the disks of each adjacent pair thereof in said row, an electrical conductor spring at each end of said row yieldably holding the disks together while permitting bodily movement of the row longitudinally in opposite directions against the resistance of one or the other of such springs, a housing of electrical insulation material enclosing said tubular member, and means carried by said housing for connecting the spring at each end of said row in a high tension circuit.
